United States Patent Office

Des. 222,558

Patented Nov. 2, 1971

222,558

LAUNDRY MACHINE

Thomas R. Smith, Newton, Iowa, assignor to The Maytag Company, Newton, Iowa

Filed Dec. 18, 1969, Ser. No. 20,564

Term of patent 14 years

Int. Cl. D15—05

U.S. Cl. D49—1

FIG. 1 is a perspective view of a laundry machine showing the front, top, and one side of my new design;

FIG. 2 is a front elevation view of the laundry machine shown in FIG. 1; and

FIG. 3 is a plan view showing the top of the laundry machine of FIG. 1.

The side not shown has substantially the same appearance as the side shown. The back is substantially unornamented.

I claim:

The ornamental design for a laundry machine, as shown and described,
